CHOCOLATE CONFECTION

Richard M. Palmer, Wyomissing, Pa., assignor to R. M. Palmer Company, West Reading, Pa., a corporation of Pennsylvania

Filed Feb. 19, 1965, Ser. No. 83,902

Term of patent 14 years

(Cl. D82—2)

FIG. 1.

FIG. 2.

FIG. 3.

FIG. 4.

FIG. 5.

FIG. 6.

FIG. 1 is a side view of a chocolate confection in accordance with my new design.

FIG. 2 is a view of the side opposite thereto.

FIG. 3 is a top view of FIG. 1.

FIG. 4 is a bottom view of FIG. 1.

FIG. 5 is an end elevational view of FIG. 1, as seen from the right, and

FIG. 6 is an end elevational view of FIG. 1 as seen from the left.

I claim:

The ornamental design for a chocolate confection, substantially as shown.
